DESIGN FOR A SPECTACLE FRAME

Michael Albanese and Anthony Paul, Rutherford,
N. J., assignors to Columbia Protektosite Co.,
Inc., Carlstadt, N. J., a corporation of New
Jersey

Application December 19, 1944, Serial No. 116,999

Term of patent 7 years

(Cl. D57—1)

To all whom it may concern:

Be it known that we, Michael Albanese and Anthony Paul, both citizens of the United States, and residents of Rutherford, in the county of Bergen and State of New Jersey, have invented a new, original, and ornamental Design for a Spectacle Frame, of which the following is a specification, reference being had to the accompanying drawing, forming a part thereof, and of which Figure 1 is a front view of a spectacle frame showing our new design; and Fig. 2 is a top, plan view thereof.

The dominant features of our design for a spectacle frame, specifically as illustrated, reside in the portions shown in full lines and consist

of the shallow undulating top curve whose low points at the nose piece and ends of the frame are at the same elevation, with the ends of the lens openings being defined by relatively large curves into which the upper and lower edges of the openings symmetrically extend, the lower edges of the frame adjacent to the sides thereof being substantially straight and diverging from the lens opening toward the ends of the undulating curve.

We claim:

The ornamental design for a spectacle frame, substantially as shown and described.

MICHAEL ALBANESE.
ANTHONY PAUL.
